[57] CLAIM

The ornamental design for a shielding box, as shown and described.

DESCRIPTION

FIG. 1 is a top view in plan of a shielding box showing my new design;

FIG. 2 is a bottom view in plan thereof;

FIG. 3 is a right side view in elevation thereof;

FIG. 4 is a left side view in elevation thereof;

FIG. 5 is a front view in elevation thereof;

FIG. 6 is a rear view in elevation thereof;

FIG. 7 is a perspective view of the shielding box showing the front, top and left sides thereof; and,

FIG. 8 is a perspective view of the inside of the shielding box when the shielding box is opened by lifting the top portion thereof.
